US0D1001729S

(12) **United States Design Patent** (10) Patent No.: **US D1,001,729 S**
(45) Date of Patent: ** Oct. 17, 2023

(54) **CHARGING STATION FOR ELECTRIC VEHICLES**

(71) Applicant: **GONGNIU GROUP CO., LTD.**, Ningbo (CN)

(72) Inventors: **Zilong Wang**, Cixi (CN); **Yingjie Sun**, Cixi (CN)

(**) Term: **15 Years**

(21) Appl. No.: **35/515,602**

(22) Filed: **Oct. 24, 2022**

(80) **Hague Agreement Data**

Int. Filing Date: **Oct. 24, 2022**

Int. Reg. No.: **DM/224770**

Int. Reg. Date: **Oct. 24, 2022**

Int. Reg. Pub. Date: **Nov. 18, 2022**

(30) **Foreign Application Priority Data**

Apr. 29, 2022 (CN) 202230253231.9

(51) **LOC (14) Cl.** **13-02**

(52) **U.S. Cl.**

USPC **D13/107**

Primary Examiner — Rosemary K Tarcza

Assistant Examiner — Seth David Kumpf

(57) **CLAIM**

The ornamental design for a charging station for electric vehicles, as shown and described.

DESCRIPTION

1. Charging station for electric vehicles

1.1 : Front

1.2 : Back

1.3 : Left

1.4 : Right

1.5 : Top

1.6 : Bottom

1.7 : Perspective

1.8 : Perspective

The broken lines in the figures show portions of the charging station for electric vehicles that form no part of the claimed design.

1 Claim, 8 Drawing Sheets
